Specification for Design.

Patented Sept. 26, 1916.

Application filed August 11, 1915. Serial No. 45,059. Term of patent 14 years.

To all whom it may concern:

Be it known that I, CHAUNCEY W. ABBOTT, a citizen of the United States, residing at Pittsburgh, in the county of Allegheny and State of Pennsylvania, have invented a new, original, and ornamental Design for Drop T-Bases for Fittings for Electrical Conduits, of which the following is a specification, reference being had to the accompanying drawing, forming part thereof.

In the drawings, Figure 1 is a bottom plan

view; Fig. 2 is an end elevation; and Fig. 3 is a side elevation from the left of Fig. 2, of a drop T-base for fittings for electrical conduits, showing the new design.

I claim:

The ornamental design for a drop T-base for fittings for electrical conduits, as shown.

CHAUNCEY W. ABBOTT.
